UNITED STATES PATENT OFFICE.

EDWARD A. SCHREIBER, OF CHICAGO, ILLINOIS.

VESTIBULE-DIAPHRAGM FOR RAILWAY PASSENGER-CARS.

1,104,938.

Specification of Letters Patent.

Patented July 28, 1914.

Application filed January 12, 1914. Serial No. 811,598.

To all whom it may concern:

Be it known that I, EDWARD A. SCHREIBER, a citizen of the United States, residing at Chicago, in the county of Cook and State of Illinois, have invented certain new and useful Improvements in Vestibule-Diaphragms for Railway Passenger-Cars, of which the following is a specification.

My invention relates to railway car vestibules, and has for its object to provide a bellows diaphragm for car vestibules composed largely, preferably wholly, of metal, which will be inexpensive to manufacture, light in weight, strong and durable, which will be so constructed as to accommodate itself to the various movements of the cars between which it is placed, and which, for these and other reasons, can be employed to advantage in place of the canvas diaphragms commonly used at the present time. The bellows diaphragm of a car vestibule must be capable, in the first place, of readily collapsing and expanding as a whole when the face plate is moved toward or away from the car. In rounding a curve the diaphragm has to collapse on one side and expand on the other. Besides this, the diaphragm of a car vestibule should be capable of absorbing the up and down and transverse vibrations of the cars to which they are attached so as to prevent, or at least to minimize, the chafing of the face plates. The fact is that the adjacent ends of two cars in a railway train in motion frequently shift their relative positions with respect to each other due to curves and differences in level of the rails, and besides this are subjected to continual vibratory movements both vertical and transverse due to the elasticity of the rails and of the springs on which the cars are mounted, inequalities in the track and other causes. My invention, in substituting metal for cloth in the construction of a vestibule diaphragm takes account of these movements and provides a structure which, while being less expensive and more durable than the canvas diaphragms, will, to all intents and purposes, be as flexible and as capable of accommodating itself to the shifting and vibratory movements of the car as are the familiar type of canvas diaphragm.

The invention is illustrated, in certain

preferred constructions, in the accompanying drawings wherein—

Figure 1 is an end elevation of a railway car furnished with a vestibule diaphragm embodying one form of the invention; Fig. 2, a sectional plan taken on line 2—2 of Fig. 1; Fig. 3, a detail plan section like that shown in Fig. 2 but on a larger scale; Fig. 4, a view, in perspective, of the diaphragm and face plate showing parts of the flooring and end wall structure of the car; Fig. 5, a detail view of one of the corner panels of the diaphragm; Fig. 6, an end view of this element; Fig. 7, a sectional view, on line 7—7 of Fig. 4; Figs. 8, 9 and 10, sectional views illustrating the construction particularly of the upper part of the diaphragm, Fig. 8 being a sectional view on line 8—8 of Fig. 9, and Figs. 9 and 10, sectional views on lines 9—9 and 10—10, respectively of Fig. 8; Fig. 11, a view, in perspective, of one of the top panels; Fig. 12, a fragmentary view, in perspective, of one of the side panels; Fig. 13, a similar view of another side panel, and Fig. 14, a view, in perspective, of a modified construction in which the diaphragm is made up very largely but not wholly of metal parts.

Like characters of reference designate like parts in the several figures of the drawings.

Referring first to Figs. 1 to 13 inclusive, 25 designates the end wall of a railway car, 26 the flooring of the car and 27 the diaphragm face plate of the vestibule. The diaphragm is made up, in the preferred construction shown in these figures, of two sets of side panels, a set of top panels and two sets of corner panels; all of sheet metal, the panels of each set being hinged together along their meeting edges. Preferably the panels are mounted upon sets of arched rods, the hinges being formed by interlocking beads.

In the construction shown each set of side panels comprises three panels 28 (Fig. 12) each formed with a large bead 29 on one edge and a smaller bead 30 on the other, a panel 28^a (Fig. 13) formed with oppositely turned beads 32 having the same diameter as the smaller beads 30 of the panels 28, and a pair of attaching members or panels 33 having beads 34 of the same diameter as the

larger beads 29 on the panels 28. The panels are mounted on two arched rods 35 and three rods 36 which latter are bent to form narrower, shorter arches. The interlocking relation between the side panels is best shown in Figs. 2 and 3.

The top structure consists of attaching members 37, 37 secured to the end wall of the car and to the face plate respectively, 10 and formed with beads 38 (Fig. 9); three panels 39 (Fig. 11) each formed at one end with a small bead 40 and at the other end with a larger bead 41, both beads being bent in the same direction from the plane of the 15 panel; and a single panel 39^a which is like the panels 39 except that its two beads 42, 43 are bent in opposite directions and are of the same diameter.

The spaces between the side panels and 20 the top panels are closed by two sets of corner panels having the same bellows-like collapsing relationship with each other as the side and top sets. The corner set consists, in each case, of attaching members 25 44, 44 (Figs. 4 and 7); three panels 45 (Figs. 5 and 6) each formed with a large bead 46 and a smaller bead 47; and a single panel 45^a like the panels 45 except that its beads 48, 49 are of the same diameter and 30 are bent in opposite directions from the plane of the panel. It will be understood that the difference in the form of the elements 28^a, 39^a and 45^a from the corresponding panels 28, 39 and 45 is necessitated by 35 the anchoring of the attaching members 33, 37, 44 to the end wall of the car and the face plate. Different expedients might be used for accomplishing the desired end but the one described I consider the most advanced.

Preferably the corner panels 45, 45^a have an overlapping relationship with the side panels and top panels. As shown in Fig. 5 each panel 45 (and the same is true of panel 45^a which differs from panel 45 only in the respect noted) is formed with an extension 50 which extends under the corresponding top panel 39 and, at the other extremity, with an extension 51 which overlies the corresponding side panel 28; the extension 51 being bent twice upon itself so as to provide a U-shaped part 52 adapted to receive and hold in place the upper end of the side panel (Figs. 6 and 10). The beads 41 of each of 55 the top panels are formed with flared or enlarged projections 53 which inclose the upper ends of the beads 46 of the corner panels. The lower extremities of the beads 46 are formed with the flared projections 54 inclosing the upper ends of the beads 29 of the side panels.

It will be seen that although the bellows diaphragm above described is constructed entirely of metal parts and forms an entirely closed structure, relatively weather-

proof (although it will preferably be covered with the usual apron—not shown) the structure will, nevertheless, possess, to all intents and purposes, the flexibility and capacity for adjusting itself to the shifting 70 and vibratory movements of the cars between which it is placed possessed by the canvas diaphragms commonly used at the present time. It can collapse as a whole. One side can collapse while the other expands. The parts are fitted together loosely enough so that the vertical and transverse vibrations of the car are absorbed and chafing of the face plates prevented. At the same time the structure can be made 75 more cheaply than the ordinary canvas diaphragm and will be much more durable. 80

In Fig. 14 I have shown a modified construction consisting of side panels 55 and a set of top panels 56, the panels of each set 85 being united together in hinged relation by interlocking beads as in the construction previously described. In this case, however, instead of using the continuous arched rods I preferably use straight vertical rods 57 90 for the side panels and straight horizontal rods 58 for the top panels. Instead of employing metal corner panels for closing the corner spaces this construction employs fabric corner pieces 59 each of which is riveted to a pair of side panels and a pair of top panels and which may be made of waterproof duck or other suitable material. 95

While I have described my invention as embodied in certain preferred constructions, 100 it will be understood that modifications might be made without departing from the principles of the invention. Therefore I do not wish to be understood as limiting the invention to the precise constructions, arrangements and devices shown except so far as such constructions, arrangements and devices are made specific limitations in certain of the claims herein. 105

I claim:

1. A bellows diaphragm for car vestibules composed of a plurality of supporting members and a plurality of sheet metal panels hinged at opposite edges to said supporting members and forming with said supports a 115 closed collapsing arched structure.

2. A bellows diaphragm structure for car vestibules comprising a plurality of sets of sheet metal panels, the panels of each set being hinged together and supporting elements which sustain said sets of panels and the extremities of the panels of one set overlapping the panels of the adjacent set. 120

3. A bellows diaphragm structure for car vestibules comprising a plurality of arched rods, and a plurality of sets of metal panels hinged to said rods, the panels of said sets overlapping the panels of adjacent sets. 125

4. A bellows diaphragm for car vestibules comprising a plurality of arched rods and 130

- a plurality of sheet metal panels hinged at opposite edges to said rods and forming with said rods a closed arched collapsible structure.
5. A bellows diaphragm structure for car vestibules comprising a plurality of sheet metal panels provided at their meeting edges with interlocking hinge forming beads, and supporting rods within said vestibules comprising two sets of side panels, a set of top panels and two sets of corner panels, the panels of each set being formed of sheet metal and provided at their meeting edges with interlocking hinge forming beads, said panels being capable of slight movement in the direction of their length and one set of panels being overlapped upon the adjacent set, and arched supporting rods extending through said beads.
10. A bellows diaphragm structure for car vestibules comprising two sets of side panels, a set of top panels, the panels of each set being formed of sheet metal and provided at their meeting edges with interlocking hinge forming beads, and corner elements completing the structure between the side and top panels.
15. A bellows diaphragm structure for car vestibules comprising two sets of side panels, a set of top panels and two sets of corner panels, the panels of each set being formed of sheet metal and hinged together at their meeting edges.
20. A bellows diaphragm structure for car vestibules comprising two sets of side panels, a set of top panels and two sets of corner panels, the panels of each set being formed of sheet metal and hinged together at their meeting edges.
25. A bellows diaphragm structure for car vestibules comprising two sets of side panels, a set of top panels and two sets of corner panels, the panels of each set being formed of sheet metal and hinged together at their meeting edges, the corner panels having an overlapping relation with the top and side panels.
30. A bellows diaphragm structure for car vestibules comprising two sets of side panels, a set of top panels, the panels of each set being formed of sheet metal and provided at their meeting edges with interlocking hinge forming beads at their meeting edges, and corner elements completing the structure between the side and top panels.
35. A bellows diaphragm structure for car vestibules comprising two sets of side panels, a set of top panels and two sets of corner panels, the panels of each set being formed of sheet metal and provided at their meeting edges with interlocking hinge forming beads, the corner panels extending under the top panels and being formed with pockets to receive the upper ends of the side panels.
40. A bellows diaphragm structure for car vestibules comprising two sets of side panels, a set of top panels and two sets of corner panels, the panels of each set being formed of sheet metal and provided at their meeting edges with interlocking hinge forming beads.
45. A bellows diaphragm structure for car vestibules comprising two sets of side panels, a set of top panels and two sets of corner panels, the panels of each set being formed of sheet metal and provided at their meeting edges with interlocking hinge forming beads, and arched supporting rods on which said panels are mounted.
50. A bellows diaphragm structure for car vestibules comprising two sets of side panels, a set of top panels and two sets of corner panels, the panels of each set being formed of sheet metal and provided at their meeting edges with interlocking hinge forming beads, said panels being capable of slight movement in the direction of their length and one set of panels being overlapped upon the adjacent set.
55. A bellows diaphragm structure for car vestibules comprising two sets of side panels, a set of top panels and two sets of corner panels, the panels of each set being formed of sheet metal and provided at their meeting edges with interlocking hinge forming beads, the adjacent ends of the panels having an overlapping relation, and the ends of the beads on certain panels being enlarged to admit and give play to the ends of the beads on adjacent panels.
60. A bellows diaphragm structure for car vestibules comprising a plurality of arched
70. A bellows diaphragm structure for car vestibules comprising two sets of side panels, a set of top panels and two sets of corner panels, the panels of each set being formed of sheet metal and provided at their meeting edges with interlocking hinge forming beads, the corner panels extending under the top panels and over the side panels.
75. A bellows diaphragm structure for car vestibules comprising two sets of side panels, a set of top panels and two sets of corner panels, the panels of each set being formed of sheet metal and provided at their meeting edges with interlocking hinge forming beads, the corner panels extending under the top panels and being formed with pockets to receive the upper ends of the side panels.
80. A bellows diaphragm structure for car vestibules comprising two sets of side panels, a set of top panels and two sets of corner panels, the panels of each set being formed of sheet metal and provided at their meeting edges with interlocking hinge forming beads, the corner panels being formed with pockets to receive the upper ends of the side panels.
85. A bellows diaphragm structure for car vestibules comprising two sets of side panels, a set of top panels and two sets of corner panels, the panels of each set being formed of sheet metal and provided at their meeting edges with interlocking hinge forming beads, the corner panels extending under the top panels and being formed with pockets to receive the upper ends of the side panels.
90. A bellows diaphragm structure for car vestibules comprising two sets of side panels, a set of top panels and two sets of corner panels, the panels of each set being formed of sheet metal and provided at their meeting edges with interlocking hinge forming beads, the corner panels being formed with pockets to receive the upper ends of the side panels.
95. A bellows diaphragm structure for car vestibules comprising two sets of side panels, a set of top panels and two sets of corner panels, the panels of each set being formed of sheet metal and provided at their meeting edges with interlocking hinge forming beads, the corner panels being formed with pockets to receive the upper ends of the side panels.
100. A bellows diaphragm structure for car vestibules comprising two sets of side panels, a set of top panels and two sets of corner panels, the panels of each set being formed of sheet metal and provided at their meeting edges with interlocking hinge forming beads, the corner panels being formed with pockets to receive the upper ends of the side panels.
105. A bellows diaphragm structure for car vestibules comprising two sets of side panels, a set of top panels and two sets of corner panels, the panels of each set being formed of sheet metal and hinged together at their meeting edges, one set of said panels being formed with pockets which receive the ends of the adjacent panels.
110. A bellows diaphragm structure for car vestibules comprising two sets of side panels, a set of top panels and two sets of corner panels, the panels of each set being formed of sheet metal and provided at their meeting edges with interlocking hinge forming beads, the adjacent ends of the panels having an overlapping relation.
115. A bellows diaphragm structure for car vestibules comprising two sets of side panels, a set of top panels and two sets of corner panels, the panels of each set being formed of sheet metal and provided at their meeting edges with interlocking hinge forming beads, the adjacent ends of the panels having an overlapping relation, and the ends of the beads on certain panels being enlarged to admit and give play to the ends of the beads on adjacent panels.
120. A bellows diaphragm structure for car vestibules comprising a plurality of arched
125. A bellows diaphragm structure for car vestibules comprising a plurality of arched
130. A bellows diaphragm structure for car vestibules comprising a plurality of arched

rods, two sets of side panels, a set of top panels and two sets of corner panels, all of sheet metal and provided with hinge forming heads engaging said rods, the corner panels having an overlapping relation with the top panels and being formed with pockets adapted to receive the upper ends of the

side panels, and the beads on the corner panels having a telescopic relation with the beads on the side and top panels.

EDWARD A. SCHREIBER.

H. M. GILLESPIE.**

It is hereby certified that in Letters Patent No. 1,104,938, granted July 28, 1914, upon the application of Edward A. Schreiber, of Chicago, Illinois, for an improvement in "Vestibule-Diaphragms for Railway Passenger-Cars," an error appears in the printed specification requiring correction as follows: Page 2, line 121, for the word "and" read *with*; and that the said Letters Patent should be read with this correction therein that the same may conform to the record of the case in the Patent Office.

Signed and sealed this 25th day of August, A. D., 1914.

[SEAL.]

J. T. NEWTON,

Acting Commissioner of Patents.
